TIME DELAY RELAY CONTROL

Gottdank L. Kothny, Strafford, and George A. Smith, Philadelphia, Pa., assignors to Sperry-Sun Well Surveying Company, Philadelphia, Pa., a corporation of Delaware

Application June 29, 1940, Serial No. 343,182

6 Claims. (Cl. 175—320)

This invention relates to a well surveying device, and has particular reference to a timing means for determining the time of making a record.

In single shot photographic well surveying devices, for example, of the type of that disclosed in the patent to Hewitt, 2,116,350, dated May 3, 1938, the time at which the exposure is made and the duration of the exposure are controlled by means of a watch controlling an electrical switch. Such a timing means must necessarily be of very small size to fit inside small size instruments and is of a very delicate nature. Its delicate mechanism, furthermore, must make the electrical contact which must carry a substantial amount of current. It will be evident that these requirements and limitations of size render the timing mechanism quite costly and subject to trouble because of the rough handling and dirt to which it is subjected at a drilling rig.

Not only photographic instruments, but other well surveying instruments as well require timing devices to determine the time at which a record is made and, in some cases, the duration of operation to complete a record. Examples of such well surveying devices are the spark recording instrument of Smith Patent 2,152,671, dated April 4, 1939, and the electrolytic recording instrument of Ring application Serial No. 313,706, filed January 13, 1940. In the case of the latter instrument, there are occasions when timing rather than control by handling may be desirable.

It is the object of the present invention to provide a timing device for a well surveying instrument in which flow of liquid is used to control the timing and in which the timing is effected electrically.

In considering timing by means of a liquid, the use of mercury is suggested. The use of mercury involves, however, first the use of special materials which are not affected by the mercury, and second the design of an orifice to a quite high degree of precision. This is due to the fact that the surface tension of mercury is very high, as is also its density. As a result, very minute changes in diameter of an orifice vary to a great degree the rate of flow of mercury therethrough, and it becomes difficult to standardize timing devices for production in quantities. The orifices are, furthermore, necessarily very small for mercury to secure flow over a considerable period using a reasonable quantity of the liquid. Very slight amounts of dirt or impurity in the mercury may close the orifice

entirely or interfere seriously with the timing by substantially changing its surface tension.

While mercury can be used with the exercise of care, taking into account the factors mentioned above, such difficulties can be avoided to a large extent by using an aqueous electrolyte in place of mercury. An aqueous electrolyte controlling the flow of current, however, offers difficulties because of the electrolysis which will 10 occur. Even the small currents after repeated operations will cause electrolysis damaging electrodes and, unless the electrolyte is properly chosen, liberate gas which could not be tolerated in a closed instrument such as should be used, 15 the timing device being preferably, as will be obvious hereafter, in the form of a sealed element, the device presenting exteriorly only electrical connection means.

The present invention is directed to solution 20 of the problem of using in satisfactory fashion an aqueous electrolyte as a timing medium for a well surveying instrument. The timing device is, furthermore, adapted to be set into operation merely by inversion.

25 The above and other objects of the invention, particularly relating to details, will become apparent from the following description, read in conjunction with the accompanying drawing, in which:

30 Figure 1 is a vertical axial section taken through one form of well surveying instrument embodying the timing device;

Figure 2 is a vertical axial sectional view through the timing element; and

35 Figure 3 is a wiring diagram of the timing element and its electrical connections.

The well surveying instrument illustrated is, generally speaking, of the type described in said Hewitt Patent 2,116,350, and comprises a protective casing 2, provided with a lower nose plug 4 and an upper plug 6 to which a wire line is to be attached for lowering the instrument in a bore hole. The operating parts of the surveying instrument are contained in an inner casing 8 within which is located a floating compass 10, a pendulum 12 and a lens 14 for projecting images of the pendulum and compass upon a photographically sensitized disc 16 held in a clamping device 18 of conventional character. To produce the 45 photographic exposure providing the record there are provided one or more lamps 20 adapted to illuminate the compass and pendulum. In this type of instrument, a timing device, heretofore a watch as described above, has been used to delay 50 illumination of the lamps for a period sufficient to 55

permit the location of the instrument where the record is to be made and then to provide illumination for a sufficient period to effect the making of a record. The various record elements are shown merely for the purpose of illustration, as it will be evident that they may take any of the forms common in the art; for example, the compass may be omitted if the instrument is merely to give a record of inclination; or a pair of compasses without a pendulum or other inclination indicating device may be provided if the instrument is to be used for orientation of tools in accordance with, for example, Hyer Patent 2,120,670, dated June 14, 1938. In fact, as will be pointed out later, the lamps 20 are merely representative of devices of other types which may be electrically energized to produce records.

Located above the recording devices are devices indicated at 22 including batteries and other elements, for example, a relay and circuit breakers, which are illustrated in the wiring diagram of Figure 3. Above these elements there is indicated at 24 a timing device per se. At the top of the timing device is an electrical contact member 54 arranged to engage a contact making spring 28 carried by a cap 26 of the casing 8.

The timing device is illustrated in detail in Figure 2, and comprises upper and lower cylinders 30 and 32, respectively connected by a member 34 which provides a bottom wall for the upper cylinder and a top wall for the lower one. The top of the upper cylinder is closed by a cap member 36 and the lower end of the lower cylinder by a cap member 38. As will be evident hereafter, these closures are to be of a substantially permanent nature to be removed only in the event that repairs or replacements are required. Preferably these ends are brazed or soldered in position after the apparatus is assembled.

Communicating with an opening in the member 34 is a tube 40 which, at its lower end, carries a calibrated orifice member 42 designed to control the slow flow of liquid from the upper into the lower chamber. Also communicating with an opening in the member 34 is a tube 44, which extends adjacent the top of the upper cylinder 30.

An electrode disc 46 is carried by an insulating member 48 provided with one or more openings 49 extending through it to provide for the free passage of liquid. A set screw 50 holds the member 48 in fixed position in the cylinder 30. The electrode 46 is connected by means of an insulated wire 52 to the contact element 54 previously mentioned, which is set in an insulating insert 56 in the cap 36.

A second electrode 58 in the form of a disc is located in the lower cylinder 32, being held in the upper end of a Bakelite or similar insert 60 provided with one or more openings 64 to permit free passage of fluid and held in position in the cylinder by means of a set screw 62. As will be described hereafter, bridging between the electrode 58 and the walls of the cylinder 32 by liquid should involve the highest resistance possible, and consequently below the electrode 58 the member 60 is desirably provided with a skirt portion 65 to interrupt liquid continuity even in the form of a film between the electrode 58 and the walls of the cylinder. Additionally, an insulated deflector member 59 is preferably located above the disc 58 to deflect from the disc the liquid flowing from the orifice.

The electrode 58 is connected by means of an insulated wire 66 to a contact member 68 car-

ried in an insulating insert 70 in the lower closure cap or plug 38.

In the particular wiring arrangement which will be described, the metal portions of the casing 5 of the timing device must be insulated from the casing of the apparatus, and for this purpose the upper and lower cylinders are surrounded by insulating sleeves 72 and 74, respectively, which may take the form of rubber tubing cemented to the metal cylinders.

The timing device contains an electrolyte 76 which, for example, may be a solution of a copper salt such as the sulphate or nitrate. In such case, the electrodes and all the metal parts coming in contact with the liquid, i. e., in the interiors of the cylinders 30 and 32, should be made of pure copper, so that electrolysis results merely in the solution of copper from one surface and deposition on another. Desirably conditions are so adjusted as to eliminate the release of gas. Other metals are equally applicable. For example, the interior electrode surfaces of the cylinders may be silvered, the cylinders taking the form of brass or other cylinders heavily plated with silver. In such case, the electrolyte could be a solution of silver salt. Other metallic salts are equally applicable with proper choice of the electrode and wall materials. It will be evident that instead of using the cylinder walls as electrodes, additional separate electrodes may be used. The walls form convenient electrodes, however, since requirements involving definite levels may be satisfied by predetermined positioning of small electrodes such as 46 and 58.

The timing device is associated with other elements which may be of any suitable constructions, and hence only their locations in a wiring diagram will be described with reference to Figure 3. It will be assumed that the casing is regarded as the ground of the instrument. As will be evident, however, the wiring diagram is subject to considerable change, depending on convenience. The upper electrode 46 is grounded through the element 54 and spring 28. A relay

45 78 is provided in the instrument, the coil of which is indicated at 78 in the wiring diagram of Figure 3. The armature 80 of this relay is grounded, and is adapted to engage three contacts 82, 98 and 102, when the coil 78 is energized. The 50 contact 82 is electrically connected with the lower electrode 58 of the timing device through the element 68 by means of a connection indicated at 84.

This contact 82 is connected with one end of the relay winding 78 which, at its other end, is connected to a contact 86 arranged to be engaged by a bimetallic member 88 wound with a resistance coil 90, this latter assembly providing a thermal type flasher of conventional character. The heating coil 90 is connected with a contact 92 engageable by a spring arm provided with a weight 94 adapted to vibrate as the instrument is jarred and thus break contact. A battery 96 completes this circuit to ground. Connected between the contact 98 and the end of the coil 78 opposite the contact 82 may be a resistance 100, the presence of which is desirable in the event that the relay is of a type requiring an extremely small current for its operation. The 65 current flowing through the coil 78 and resistance 100 in parallel may be relatively larger to secure operation of the flasher device, which may then be of more or less conventional nature.

A third contact 102 adapted to be engaged 70 by the armature 80 is connected to the recording

controlling element or elements illustrated conventionally in the wiring diagram as a lamp 104. A second battery 106 is located in this circuit. While two batteries 96 and 106 have been illustrated for simplicity of explanation, it will be evident that a single battery may be used both for control purposes and the making of a record. For example, a lamp or plurality of lamps might replace the resistance 100, or might be in series with the battery 96. In certain cases, however, different voltages and wiring requirements may dictate the presence of two batteries which are, therefore, indicated.

Assuming for the purpose of explanation a photographic well surveying instrument of the type illustrated in Figure 1, in which a record is made by the timed illumination of a lamp or series of lamps such as 29, indicated in the wiring diagram at 104, the device is operated as follows:

After an operation of the device is completed, the electrolyte will be located in the lower cylinder 32. Normally the timing device is kept in this position prior to assembly. When the instrument is made up for operation, it may be made up in inverted position by dropping into the protective casing the various elements after removal of the bottom plug 4. If this is done, when the timing unit is inverted prior to and during insertion, the electrolyte 16 will flow rapidly into the upper cylinder through the tube 44, venting of air from that cylinder taking place through the orifice 42. After the elements have been located in the instrument and the plug 4 screwed on, the instrument should be kept in inverted position until it is desired to lower it into the hole. The cylinder 30 is of such size and contains such amount of liquid that when the instrument is in inverted position, the electrode 46 is above the liquid surface. Thus no engagement of the liquid with electrode 46 takes place in this reverse flow. This prevents any operation during the return flow of liquid to the upper cylinder.

As the instrument starts into the bore hole after being turned to upright position and with a recording disc 16 in place, the electrical configuration will be essentially that of Figure 3. The relay and lamp 104 are deenergized so that the armature is in a retracted position. The electrolyte slowly flows through the orifice 42 at a rate determined by its opening and drops into the lower cylinder, being deflected from the electrode 58 by the deflecting element 59 above that electrode. The electrode 46 is submerged during this operation, but until the electrode 58 is submerged by accumulation of liquid in the lower cylinder, there is no circuit completed through the timing device 24. The design should be such that electrode 58 will not be reached by the liquid until the instrument is resting in the position at which the record is to be made.

The arrangement is such that the liquid rises to electrode 58 before it uncovers the electrode 46. The result is that a circuit is completed from the electrode 46 through the liquid to the wall of the upper cylinder, and thence from the wall of the lower cylinder through the electrolyte in the lower cylinder and the electrode 58. The current thus flowing immediately energizes the coil 78, attracting the armature and closing all the contacts 82, 98 and 102. The first effect that will be noted is that the armature 80 and contact 82 shunt the circuit through the timing device, short circuiting it, so that current flow through it will stop. It will thus be evident that at this time a

flow of current can occur for only a small fraction of a second. The relay resistance is desirably high (the relay being of a very sensitive type) and the result may be, therefore, the flow of no more than a few milliamperes for a very short period. The electrolysis occurring in one such circuit closure is accordingly extremely minute and represents removal and deposition of an almost immeasurable quantity of metal. The making of the contact 98 and completion of the circuit through shunt 100 provides a relatively large current flow through the flasher resistance coil 90. Heating up of this flasher then occurs with the result that after a predetermined time, which may be of the order of, say, ten seconds, the relay circuit will be opened so that the relay will drop its armature 80. As soon as cooling occurs, a moment thereafter, contact is again made between 86 and 88. If, now, the electrolyte still engages both electrodes 46 and 48, the relay is again immediately energized by a momentary flow of current through the timing device, and again the flasher begins to heat up to its breaking point. Eventually the electrolyte will uncover the electrode 46. After this occurs and an opening of the flasher circuit takes place, reclosing the flasher circuit will not effect reenergizing of the coil 78, and hence no further closure of the armature with its contacts will take place.

Whenever the armature 80 is attracted by the relay coil, the circuit through the lamp 104 is completed, and a record exposure is being made. It will be evident, therefore, that the total length of exposure will be the total of the periods of closure of the flasher circuit 88 after contact of liquid with 58, the last of which periods at its initiation finds the circuit completed in the timing device. The exposure time, therefore, is approximately that time during which both electrodes 46 and 58 are in contact with the electrolyte. It will be evident that a suitable type of flasher taken in conjunction with suitable location of the electrodes will result in any desired time of exposure. In general, of course, considerable variations in exposure are permissible by reason of the latitude of the emulsion used. If precision is required, a flasher which breaks its circuit frequently should be used. In such case, the maximum error over the period of simultaneous submergence of the electrodes is the time between breaks of the flasher circuit.

After the instrument is brought to the surface, if it is inverted for removal of the apparatus through the bottom of the casing after taking off the nose plug 4, the liquid will flow rapidly into the upper chamber 30 without completing the control circuit. Thus no second exposure will be made.

It will be evident that the timing device controls both the delay in the making of the record and the time of exposure or other operation during which the record is made. The delay before the recording operation is initiated depends upon the time required for the liquid to rise in the lower chamber to the electrode 58. The duration of the recording operation depends upon the interval between the liquids' engaging electrode 58 and dropping out of contact with the electrode 46, plus such time as is involved in the breaking of the relay circuit.

The contact arrangement illustrated at 92 and 94 is necessary only in the event that an unbalanced armature 80 is used which might, by reason of impact during the lowering of the apparatus, make accidental contact with 82. In such case, of course, the relay would be held in

closed position until breaking occurs due to the flasher 88. The arrangement at 92 and 94 may be provided to prevent this and so that vibration during motion of the instrument continuously opens and closes the circuit, with the result that more than a momentary closure to light the lamp 104 is impossible. Using balanced relays, however, which are quite insensitive to shocks of even major intensity, the arrangement at 92 and 94 may be dispensed with. In such case, closure of the circuit will not occur until caused by the liquid.

As indicated above, the lamp 104 is shown only for illustrative purposes. Instead of a lamp, a spark coil may be provided in this position to produce a spark record, or the circuit including the lamp may be taken, as representative of any other electrical circuit such as involved, for example, in the Ring application referred to above. The circuit of the lamp 104 may also involve a relay for control of valves or other mechanism involved in well surveying instruments. The timing means is, as will be evident, of quite general application in place of clock controlled or otherwise time controlled contacts.

It will be evident that the principles of the invention are of general applicability in the use of liquid for electrical timing purposes, irrespective of the particular arrangement for providing for the bridging of electrodes by the liquid. For example, it will be evident that the invention is applicable to a timing device provided by locating electrode means (one electrode, for example, being the casing) in the recording chamber of a device such as that of Winn Patent 2,134,808, dated November 1, 1938. Preferably in such case the Winn apparatus is modified so that the liquid may be returned to a supply chamber by inversion of the instrument, for example, by adopting the construction described in the application of Davis, Serial No. 310,296, filed December 21, 1939. In the use of apparatus of this general character, the completion of a circuit may be provided in a period beginning with the bridging of electrodes by liquid and ending with the removal of the liquid therefrom, rather than, as in the particular form of the invention described herein, by causing liquid to reach one pair of electrodes prior to breaking the bridge between another pair, the two pairs of electrodes being in series.

What we claim and desire to protect by Letters Patent is:

1. An electrical timing means comprising a supply chamber, a receiving chamber, means for controlling a slow flow of an aqueous electrically conductive liquid from the supply chamber to the receiving chamber, means providing electrodes in the supply and receiving chambers, a source of electricity arranged to provide a flow of current through said electrodes and liquid when the electrodes in both chambers are in contact with said liquid, and means for providing a low resistance shunt for the liquid between said electrodes promptly upon initiation of said current flow.

2. An electrical timing means comprising a supply chamber, a receiving chamber, means for controlling a slow flow of an aqueous electrically

conductive liquid from the supply chamber to the receiving chamber, means providing electrodes in the supply and receiving chambers, a source of electricity arranged to provide a flow of current through said electrodes and liquid when the electrodes in both chambers are in contact with said liquid, and a relay arranged in series with said electrodes to be actuated by said current flow and provide a low resistance shunt for the liquid when energized.

3. An electrical timing means comprising a plurality of chambers, means for controlling flow of an aqueous electrically conductive liquid from one chamber to another, electrode means arranged in a chamber to be electrically connected by said liquid after occurrence of a predetermined flow, a source of electricity arranged to provide a flow of current through said electrode means and liquid when so connected, and means controlled by a momentary passage of current through said electrode means for interrupting flow of said current therethrough.

4. An electrical timing means comprising a plurality of chambers, means for controlling flow of an aqueous electrically conductive liquid from one chamber to another, electrode means arranged in a chamber to be electrically connected by said liquid after occurrence of a predetermined flow, a source of electricity arranged to provide a flow of current through said electrode means and liquid when so connected, means controlled by a momentary passage of current through said electrode means for interrupting flow of said current therethrough, and means for periodically providing for momentary flow of said current through said electrode means as long as said electrode means are electrically connected by said liquid.

5. An electrical timing means comprising a plurality of chambers, means for controlling flow of an aqueous electrically conductive liquid from one chamber to another, electrode means arranged in a chamber to be electrically connected by said liquid after occurrence of a predetermined flow, a source of electricity arranged to provide a flow of current through said electrode means and liquid when so connected, means controlled by a momentary passage of current through said electrode means for interrupting flow of said current therethrough, and means dependent upon further flow of liquid for interrupting the circuit including said electrode means.

6. An electrical timing means comprising a plurality of chambers, means for controlling flow of an aqueous electrically conductive liquid from one chamber to another, electrode means arranged in a chamber to be electrically connected by said liquid after occurrence of a predetermined flow, a source of electricity arranged to provide a flow of current through said electrode means and liquid when so connected, and means controlled by a momentary passage of current through said electrode means for shunting said electrode means and thereby interrupting flow of said current therethrough.
